UNITED STATES PATENT OFFICE

150,369

DESIGN FOR AN ASH TRAY

Peter Narey, North Little Rock, Ark.

Application April 9, 1947, Serial No. 138,259

Term of patent 7 years

(Cl. D85—2)

To all whom it may concern:

Be it known that I, Peter Narey, a citizen of the United States, residing at North Little Rock, in the county of Pulaski and State of Arkansas, have invented a new, original, and ornamental Design for an Ash Tray, of which the following is a specification, reference being had to the accompanying drawing, forming part thereof.

I claim:

The ornamental design for an ash tray, as shown.

PETER NAREY.
